UNITED STATES PATENT OFFICE.

WILLIAM L. TAYLOR, OF CINCINNATI, OHIO.

TOBACCO BAG.

Application filed August 7, 1922. Serial No. 580,055.

To all whom it may concern:

Be it known that I, WILLIAM L. TAYLOR, a citizen of the United States, and a resident of Cincinnati, in the county of Hamilton and State of Ohio, have invented certain new and useful Improvements in Tobacco Bags, of which the following is a full, clear, and exact description, reference being had to the accompanying drawings forming part of this specification.

My invention relates to bags, such as are used for tobacco, although, of course, the bags could be used for any desired purpose.

In the production of a one-piece bag for tobacco, it is customary to provide a single blank having one half wider than the other to provide flanges or tabs which can be folded in over the blank. To these tabs cement is applied and the narrow end of the blank laid down over the tabs, so as to become cemented thereto and thereby forming a one-piece bag open at one end.

It has been found desirable by me to form bags for articles which must resist climatic conditions of moisture, penetrating odors and the like, to make them from paper which is of plural ply and pasted together with asphalt.

The asphalt makes a perfectly insulated article out of the paper if laid between the webs in an unbroken layer and is tasteless and odorless.

The difficulty in forming a perfect bag of this substance lies in the fact that its adhesiveness is not perfect, and that in cold weather it becomes hard, and in hot weather, soft to a certain degree. Thus any asphalt pasted paper is likely to separate under strain, so as to permit the webs to part, and if this should occur in a bag, it would make it useless for the purpose of a container of semi-permanent nature.

It is evident that there is exposed to strain in the single bag which I have briefly described above, the edges of the narrow ends, and that portion of the tabs to which the narrow end is cemented. The edges of the narrow end are exposed and are subject to peeling back to expose the asphalt layer, and the tabs are likely to separate from the opposite wall to which they are glued and permit the bag to come to pieces.

It is my object to so form the bag of my invention that neither of these dangers are likely to occur, and in which the asphalt filler is not likely to show at any exposed

edges of the paper, and thus to smudge over onto the face of the bag, making it unsightly.

These objects and other advantages to be noted I accomplish by that certain construction and arrangement of parts to be herein-after more specifically pointed out and claimed.

In the drawings,

Figure 1 is a plan view of the bag blank for a single bag.

Figure 2 is a section on the line 2—2 thereof, enlarged so as to show the nature of the interposed layers.

Figure 3 is a perspective view of the completed bag.

Referring to the blank, I employ the usual shape of blank for a single tobacco bag having the ends 1 and 2, with the tabs 3 located at the sides of the end 1. In forming up the bag, the end 2 is folded toward the end 1 across the center of the blank, with the tabs folded inside between the two ends of the blank. Cement is applied to the tabs or the edges of the end 2, so that the tabs and the end 2 are secured together, thereby forming a single wall bag.

The paper I employ is formed of plies A and B, between which is a binding layer of asphalt 4. This asphalt is of a tacky and resilient and odorless and tasteless quality and binds the webs of paper together. Instead of paper I might employ fabric or foil, although this will not ordinarily be called for in bags of this character which are made by machinery in great quantities, and used for scrap tobacco, cigar pouches, and the like.

In forming the asphalted web of paper, bands of cementitious material other than asphalt are provided which extend longitudinally of the sheet as indicated by the areas within the dotted lines 6 in Figure 1 and as shown in the unshaded portions 6 in Figure 2. When the web is cut into blanks, these bands are disposed along the edges of the narrow ends of the blanks and extend through the wide ends of the blanks. Other bands of suitable cementitious material are disposed along the edges of the tabs 3 as indicated by the areas included between the outer edges of the tabs 3 and the dotted lines indicated at 5 in Figure 1, and as shown by the unshaded portions 5 in Figure 2.

If cement of different color than the asphalt were to be used for the cemented

areas the appearance of the outer sides of the bag might be marred with streaks so that in order to avoid this I have found it preferable to mix a small amount of black material with the cement to give the body of the paper in the bag the same appearance throughout. A suitable cement for the areas indicated at 6 may be provided by mixing casein or varnish with asphalt, and 10 a similar material may be used for the areas indicated at 5.

Thus I show the narrow bands of casein or varnish 6, which may be applied together with enough asphalt to give a black 15 color, or which may be so applied that the asphalt can become transfused into the casein or varnish sufficiently to change its color, but not sufficiently to change its strongly adhesive nature.

20 I have not limited myself to the use of particular cementitious material for the tab portions. Casein and varnish have waterproofing qualities and could be used instead of asphalt, except for their high cost. 25 Also they could be used in a wide band, so as to take in the tabs and narrow end edges also, except for its high cost.

A good varnish mixed with a portion of asphalt or colored black, or filled in some 30 other way to give it color and bulk, can be used in smaller quantities than the cement. Thus the narrow streams sufficient to make permanent the edges of the narrow ends of the blanks are not a full thickness of pure 35 varnish necessarily. This is true also of casein, which can be applied with but little moisture and is an excellent adhesive, such that it will bind the paper together even if a slight amount of asphalt is present to 40 give color, or other black color is incorporated.

I find that a bag formed of a blank having the tab edges cemented where they are protected by the overlap of the narrow end of 45 the blank, and a narrow stream of casein or varnish running along the blank so as to safely cement together the edges of the narrow blank where exposed, gives me a thoroughly insulated bag, and a bag which 50 is clean throughout and formed of a single piece capable of being made up automatically and very rapidly in special machines made for the purpose. Such machines are now in use and have been for many years.

55 The characteristics of varnish or casein, which are vegetable and animal gums re-

spectively and which make them applicable to my purpose is that they are gummy substances and that they have insulating qualities. I wish to include in the term varnish 60 or casein such gummy, insulating substances as may be applied to a web of paper, fabric or foil, together with some asphalt or in the absence of any asphalt along the lines of the gum stream, and which will serve as 65 an adhesive of permanent nature better than asphalt.

Having thus described my invention, what I claim as new and desire to secure by Letters Patent, is:

70 1. A bag formed of a blank of foldable material, said blank having one end folded over, inturned tabs on the other end, and said first mentioned end cemented to said tabs, said blank having a plural ply nature 75 between which plies is a binding, interposed layer of asphalt or like substance, with certain portions of the blank having interposed streams of varnish, casein, or the like at the exposed lateral edges of the completed bag, 80 and said blank having a nonasphaltic cement at the edges of the inturned tabs.

2. A blank for bags comprising a single member having a wide end and a narrow end, the extending portions of the wide end 85 to serve as inturned tabs, said blank being formed of two plies, at least, of paper, fabric or foil, and the plies united by a binding interposed layer of asphalt or like substance, with a narrow stream of varnish, 90 casein or the like extending between the plies lengthwise of the blank, so as to lie at the edges of the narrow end thereof, and with the asphalt absent from lines extending lengthwise along the tab portions of the blank and in its place a permanent binding interposed band of suitable cement.

95 3. A blank for folding lengthwise to form a bag comprising a wide end and a narrow end with extended portions of the wide end 100 adapted to be folded to form sealing tabs and the blank formed of plies united by a binding interposed layer of asphalt or the like, with a narrow stream of varnish, casein or the like disposed between the plies extending lengthwise of the blank along outer edges 105 of the narrow end of the blank and extending through the wide end of the blank and means for securing the tabs and the narrow end of the blank together, to form a bag.

WILLIAM L. TAYLOR.
